UNITED STATES PATENT OFFICE.

HERBERT R. KEITHLEY, OF MICHIGAN CITY, INDIANA, ASSIGNOR TO HASKELL & BAKER CAR CO., INC., A CORPORATION OF NEW YORK.

DRAFT-ARM FOR RAILWAY-CARS.

1,258,784.

Specification of Letters Patent.

Patented Mar. 12, 1918.

Application filed July 24, 1917. Serial No. 182,462.

To all whom it may concern:

Be it known that I, HERBERT R. KEITHLEY, a citizen of the United States, and resident of Michigan City, county of La Porte, and State of Indiana, have invented certain new and useful Improvements in Draft-Arms for Railway-Cars, of which the following is a specification, and which are illustrated in the accompanying drawings, forming a part thereof.

The invention relates to draft arms adapted to reinforce and strengthen the sills of a car and to carry the draft and buffering lugs with which the coupler mechanism co-operates. More specifically, it relates to draft arms formed of pressed steel and having a portion arching over and extending beyond the car bolster.

The objects of the invention are to secure, in a device of this character, increased strength and adaptability to draft gears varying in length.

The invention consists of a structure such as is hereinafter described, and as illustrated in the accompanying drawings, in which—

Figure 1 is a detail longitudinal section of the underframing of a car, the draft arm being shown in elevation;

Fig. 2 is a plan view of the draft arm detached; and

Fig. 3 is a sectional view on the line 3—3 of Fig. 1.

The end sill of a car is represented at 10, and one of its center sills at 11. The draft arm comprises a plate having a portion 12 adapted to lie alongside of the inner face of the sill 11, its forward end abutting against the end sill 10 and its rearward end projecting over and to a considerable distance beyond the car bolster 13. The arm also comprises a portion 14 extending downwardly from the portion 12 and in the same plane therewith. The forward end of the portion 14 extends under the sill 10 and its

rearward end abuts against the bolster 13. An angle bar 15, riveted to the arm section 14, bears against the under face of the sill 11, and is secured thereto by means of bolts as 16.

An instanding flange 17 is formed along the upper margin of the arm section 12, and an outstanding flange 18 is formed along the outer margin of the section 14. The section 12 is also provided with an outstanding flange 19, extending from the forward face

of the bolster 13 to the rearward end of the arm and underlying the sill 11 and bolted thereto, as shown at 20.

A lug 21, preferably of pressed steel, is riveted to the outer face of the arm section 14 and abuts against the bolster 13, this lug fitting snugly between the flange 18 and the angle bar 15, to both of which it is preferably riveted. A draft lug 22 and a buffering lug 23 are riveted to the inner face of the arm section 14, the upper row of rivets associated with each of these lugs serving also as securing means for the angle bar 15. The buffering lug 23 may, as shown, overlap the lug 21, in which case securing rivets, as 24, 25, may be common to both. Should it be desired to space the draft and buffering lugs a greater or less distance than as indicated in the drawings, the buffering lug may be set entirely forward of the lug 21, in which case there would be no rivets common to both; or it may be set farther back, in which case more than a single set of rivets would be common to the two lugs.

In service buffering stresses are transmitted to the arm through the lug 23, and from the arm to the car frame through the bolts by which the arm is attached to the sill 11, but to a considerable extent through the bolster by reason of the bearing of the arm against the front face thereof. The lug 21 provides an extended bearing surface, and this lug is of substantial strength because of its upper and lower webs or flanges 26, 27. A tie-plate 28 is preferably riveted to the flange 19 back of the bolster 13, and abutting thereagainst, and will extend across to the companion arm, to which it will also be secured.

I claim as my invention—

1. In a draft arm for railway cars, in combination, a pressed steel plate having a portion adapted to bear against the inner face of a car sill and to extend from the end sill thereof over and beyond the car bolster and a portion extending downward and adapted to abut against the car bolster, and a lug in operative engagement with the under side of the car sill secured to the depending portion of the arm and adapted to bear against the front face of the bolster.

2. In a draft arm for railway cars, in combination, a pressed steel plate having a portion adapted to bear against the inner face of a car sill and to extend from the end

三

sill thereof over and beyond the car bolster and a portion extending downward and adapted to abut against the car bolster, and a lug in operative engagement with the under side of the car sill secured to the depending portion of the arm and adapted to bear against the front face of the bolster and having top and bottom and an end flange.

10 3. In a draft arm for railway cars, in combination, a pressed steel plate having a portion adapted to bear against the inner face of a car sill and to extend from the end sill thereof over and beyond the car bolster
15 and a portion extending downward and adapted to abut against the car bolster and having an outstanding flange at its lower margin, and a lug having top, bottom and end flanges secured to the outer face of the
20 depending portion and adapted to operatively bear against the flange thereof and against the car sill and bolster.

4. In a draft arm for railway cars, in combination, a pressed steel plate having a portion adapted to bear against the inner face of a car sill and to extend from the end sill thereof over and beyond the car bolster and a portion extending downward and adapted to abut against the car bolster, a lug in operative engagement with the under side of the car sill secured to the depending portion of the arm and adapted to bear against the front face of the bolster, and an angle bar secured to the outer face of the depending portion of the arm and adapted to bear against and to be secured to the lower face of the car sill.

lower face of the car sill.

5. In a draft arm for railway cars, in combination, a pressed steel plate having a portion adapted to bear against the inner face of a car sill and to extend from the end sill thereof over and beyond the car bolster and a portion extending downward and

adapted to abut against the car bolster, a lug secured to the depending portion of the arm and adapted to bear against the front face of the bolster, a buffering lug attached to the inner face of the draft arm, and rivets securing both of the named lugs to the arm. 45

6. In a draft arm for railway cars, in 50
combination, a plate having a portion adapt-
ed to bear against the inner face of a car
sill and to extend from the end sill thereof
over and beyond the car bolster and a por-
tion extending downward and adapted to 55
abut against the car bolster, said portion
having a flange adjacent its lower edge and
a second flange connected with the plate
and extending beneath and bearing against
said sill, and a lug secured to the depending
portion of said plate and adapted to bear
against the front face of the bolster and
having top and bottom flanges secured to
said flanges on the plate and an end flange
engaging said bolster. 60
65

7. In a draft arm for railway cars, in combination, a plate having a vertical web adapted to bear against the inner face of a car center sill, an instanding flange at the upper edge of said web, an outstanding flange at the lower edge of said web spaced from said sill, a member connected with the vertical web and seated against the lower surface of said sill, the part of said plate extending below the center sill being adapted to abut against the car bolster, the part of said plate in engagement with the inner face of said sill extending over said bolster and increasing in height adjacent said bolster, and draft and buffering lugs arranged on said web. 70 75 80
